SWIVEL-JOINTED WIRED ELECTRICAL FIXTURE

Bertram A. Wilson, Etobicoke Township,
York County, Ontario, Canada

Application October 16, 1948, Serial No. 54,981

8 Claims. (Cl. 248—278)

1

This invention relates to swivel-jointed wired electrical fixtures, and more particularly to a joint for an electric fixture to facilitate movement of an electric light bulb to a variety of angular positions.

An object of this invention is to provide an adjustable electric fixture which may be repeatedly set to a variety of angular positions without causing failure of the insulation on the electrical wires carrying current to the electric device.

A further object of this invention is to provide means whereby an incandescent bulb may be adjusted to a variety of positions, but where such continual adjustments will not cause twisting of the electric wires to thereby cause their failure.

All of the foregoing and still further objects and advantages of the invention will become apparent from a study of the following specification, taken in conjunction with the accompanying drawings, wherein like characters of reference indicate corresponding parts throughout the several views and wherein:

Fig. 1 is a side elevation of the device showing the lamp receptacle in an erect position.

Fig. 2 is an end elevation of the device shown in Fig. 1 taken on the section 2—2 in Fig. 1.

Fig. 3 is a side elevation of the device, as in Fig. 2 but showing the lamp receptacle and tubular member rotated through its full excursion of 90° about the longitudinal axis of the tubular member; and

Fig. 4 is a section through the device on the line 4—4 in Fig. 3.

Referring to all the figures, a base member or supporting shell 5 is adapted to be mounted on a suitable surface such as a wall (not shown) by means of a screw 6 passing through a hole 7 in shell 5. A threaded hole 8 extends through the crown of supporting shell 5 and carries therein an externally threaded nipple 9 upon which is threaded a nut or collar 10. In the drawings, collar 10 is shown as having a hexagonal outer contour. Resting upon the outer end of collar 10 is a substantially U-shaped channel-shaped saddle 11 having a hole 11a in its web adapted to register with the passage through collar 10. A hollow cylindrical member 12 having a diameter substantially greater than the breadth of saddle 11 is embraced by the arms of the saddle and rests longitudinally therein, the outer edge of the arms of the saddle 11 bearing against the outer periphery of cylindrical member 12. A slot 13 having a breath slightly greater than the diameter of the hole in the saddle 11 and collar 10 extends over approximately one-quarter of the periphery of the curved wall of said cylindrical member. A nipple 14 of the same diameter as

2

that of nipple 9 and having a transversely outwardly extending shoulder 15 thereon, extends through slot 13, passage 11a, and thence is screwed into collar 10, the two nipples 14 and 9 forming, in combination, a conduit extending from the base member 5 to the interior of the cylindrical member 12 to carry a wire. A helical spring 16 bearing against the underside of shoulder 15 presses cylindrical member 12 within saddle 11 to thereby provide frictional engagement therebetween, and through the medium of saddle 11 member 12 is pressed into frictional engagement with collar 10.

Nipples 9 and 14 are hollow in order to permit passage therethrough of a pair of insulated flexible electrically conducting wires which carry current to a lamp receptacle 17 which is mounted on conduit 26 threaded into cylindrical member 12. It will be evident that, by gripping receptacle 17, tubular member 12 may be rotated about its longitudinal axis through approximately 90° and, due to the frictional forces existing between the extremities of saddle 11 and the periphery of tubular member 12, may be set to any position between the two extremes of rotation. It should also be evident that saddle 11 may be rotated about the longitudinal axis of screw 9 and nipple 14 through almost a complete rotation of 360° and due to the friction between collar 10 and saddle 11, may be set at any desired position within that range. The result of the provision of these two degrees of rotation is therefore a receptacle which may be turned and set to virtually any angular position within the limits of a geometrical half-sphere.

A set screw 18 is threaded through collar 10 and can be tightened against nipple 14 to retain it in the collar. To prevent the flexible insulating wires which pass through screw 9 and nipple 14 from becoming twisted about each other due to continual rotation in one direction, a projection 20 extends downwardly from the lower face of saddle 11 to engage the set screw 18 and thus prevent the cylindrical member from rotating more than 360° about the longitudinal axis of the nipples 9 and 14. Therefore the electrically conducting cord cannot become twisted so as to cause failure thereof.

A further characteristic of this invention is the inclusion of a fibre strip 21 which extends around approximately three-quarters of the inner periphery of cylindrical member 12. A slot 22 in the fibre strip provides a passage through which nipple 14 extends. In order to protect the strip 21 from wear due to direct pressure thereon by helical spring 16, a concavo-convex bearing washer 23 is provided around the nipple as shown

in Figs. 2 and 3. Slot 22 in strip 21 is chosen to have a length approximately one-half that of slot 13 in cylindrical member 12. As tubular member 12 is rotated about its longitudinal axis from one extreme of rotation to the other, the two extremes being shown in Figs. 2 and 3, it will be seen that strip 21 will co-operate with the bearing washer 23 to close the slot 13. Plates 24 and 25 are provided for closing the ends of cylindrical member 12 to provide a completely closed chamber therein.

Since a slot is provided in the fibre strip 21 in order that it may slide relatively to nipple 14 over a restricted range, whether or not strip 21 rotates with cylindrical member 12 when the latter is rotated about its longitudinal axis or whether it remains stationary relatively to the nipple, depends upon the relative coefficients of friction between the fibre strip and the cylindrical member and between the fibre strip and the concavo-convex bearing washer. Clearly, if the coefficient of friction between the fibre strip and tubular member is greater than the coefficient of friction between the fibre strip and the bearing washer, the fibre strip will rotate along with the tubular member relatively to the nipple, and a sliding action will take place between the bearing washer and the fibre strip, until the fibre strip has rotated so that the trailing edge of the slot therein bears against the nipple, and thereafter fibre strip 21 will slide relatively to the cylindrical member. Thus it will be seen that, as the lamp receptacle is rotated from one extreme to the other about the axis of rotation of the cylindrical member 12, fibre strip 21 will at all times be advanced so as to cover slot 13 in the cylindrical member as the slot appears from saddle member 11.

Taking the other possibility, where the coefficient of friction between the fibre strip and the inner surface of the cylindrical member 12 is less than the coefficient of friction between the fibre strip 21 and the bearing washer 23, the operation of the device is somewhat different. In this instance, threaded conduit 26 by means of which receptacle 17 is secured to cylindrical member 12, plays a part in the operation of fibre strip 21. As an example of its operation, movement of the lamp from the position shown in Fig. 3 to that shown in Fig. 2 will be described. As receptacle 17 is raised, thereby rotating cylindrical member 12 in a clockwise direction about its longitudinal axis, fibre strip 21 slides within member 12. This sliding action continues until the trailing edge 21 of strip 21 bears against the leading edge of threaded conduit 26 which projects a short distance within tubular member 12. Fibre strip 21 is thereupon forced to rotate along with cylindrical member 12 and to slide relatively to bearing washer 22 with which it had previously been in stationary contact, so that, as shown in Fig. 2, the leading edge 28 of fibre strip 21 has advanced to cover the opening in slot 13.

It should be noted that the optimum frictional forces in this device may be found conveniently by loosening set screw 18 and adjusting the extent to which nipple 14 extends within collar 10 so as to vary the pressure of helical spring 16. In the preferred construction nipple 14 is threaded within collar 10 so that by axially rotating nipple 14 within collar 10 the nipple may be easily advanced or retracted. After the desired spring pressure has been found, set screw 18 is tightened upon nipple 14 to prevent its moving from that position.

It is thought that the construction and use of the invention will be apparent from the above description of the varicous parts and their purpose. It is to be understood that the form of the invention herewith shown and described is to be taken as a preferred example of the same and that various changes in the shape, size and arrangement of parts may be resorted to, without departing from the spirit of the invention or the scope of the subjoined claims.

What I claim as my invention is:

1. A swivel jointed wired electrical fixture adapted for universal angular adjustment comprising a round hollow member having a slot of greater length than width in its curved wall and extending peripherally thereof and a hole in its curved wall spaced peripherally from the ends of the slot, a base member, a conduit adapted to carry a wire and supported at one end in said base member and extending through the slot to the interior of the round hollow member and being provided with a transversely extending shoulder adjacent its other end, spring means compressed between said shoulder and the inner surface of the round member adjacent the slot for pressing the round member into frictional engagement with the base member, and another conduit adapted to carry a wire, said other conduit communicating with the hole in the round member and being secured to and projecting outwardly from the curved side of the round member.

2. A swivel jointed electrical fixture adapted for universal angular adjustment comprising a cylindrical hollow member having a slot of greater length than width in its curved wall and extending peripherally thereof and a hole in its curved wall spaced from the ends of the slot, a supporting member, a conduit adapted to carry a wire and supported at one end in said supporting member and extending through the slot to the interior of the cylindrical member and being provided with a transversely extending shoulder adjacent its other end, spring means compressed between said shoulder and the inner surface of the cylindrical member adjacent the slot for pressing the round member into frictional engagement with the supporting member, another conduit adapted to carry a wire, said other conduit communicating with the hole in the cylindrical member and being secured to and projecting outwardly from the curved side of the cylindrical member, and a substantially U-shaped channel member supported by the supporting member and having a hole therein through which the first conduit passes, the arms of the channel member embracing the cylindrical member which lies longitudinally between them.

3. A swivel jointed wired electrical fixture adapted for universal angular adjustment comprising a round hollow member having a slot of greater length than width in its curved wall and extending peripherally thereof and a hole in its curved wall spaced peripherally from the ends of the slot, a base member, a conduit adapted to carry a wire and supported at one end in said base member and extending through the slot to the interior of the round hollow member and being provided with a transversely extending shoulder adjacent its other end, spring means compressed between said shoulder and the inner surface of the round member adjacent the slot for pressing the round member into frictional engagement with the base member, another conduit adapted to carry a wire, said other conduit com-

municating with the hole in the round member and being secured to and projecting outwardly from the curved side of the round member, and interengaging stop members between the round member and supporting member to limit rotation of the round member about the longitudinal axis of the first mentioned conduit.

4. A swivel jointed wired electrical fixture adapted for universal angular adjustment comprising a round hollow member having a slot of greater length than width in its curved wall and extending peripherally thereof and a hole in its curved wall spaced peripherally from the ends of the slot, a supporting member, a nipple adapted to carry a wire and supported at one end in the supporting member and extending through the slot in the round member and having a transversely extending shoulder adjacent its other end, spring means compressed between the shoulder and the inner surface of the round member adjacent the slot for pressing the round member into frictional engagement with the supporting member, said nipple being longitudinally adjustable within said supporting member so as to vary the compression of the spring means, means for locking the nipple in place after adjustment, and a conduit adapted to carry a wire, said conduit communicating with the hole in the round member and being secured to and projecting outwardly from the curved side of the round member.

5. A swivel jointed wired electrical fixture adapted for universal angular adjustment comprising a round hollow member having a slot of greater length than width in its curved wall and extending peripherally thereof and a hole in its curved wall spaced peripherally from the ends of the slot, a supporting collar, a nipple supported at one end in the collar and adapted to carry a wire, a set screw for retaining the nipple in the collar, a channel-shaped saddle resting on said collar and having a hole therein through which the nipple passes, the ends of the saddle bearing against the round member, a downward projection on said saddle for engaging the set screw to act as a stop to limit rotation of the round member about the longitudinal axis of the nipple, and a conduit adapted to carry a wire, said conduit communicating with the hole in the round member and being secured to and projecting outwardly from the curved side of the round member.

6. A swivel jointed wired electrical fixture adapted for universal angular adjustment comprising a round hollow member having a slot of greater length than width in its curved wall and extending peripherally thereof and a hole in its curved wall spaced peripherally from the ends of the slot, a supporting member, a nipple adapted to carry a wire and supported at one end in the supporting member and extending through the slot in the round member and having a transversely extending shoulder adjacent its other end, spring means compressed between the shoulder and the inner surface of the round member adjacent the slot for pressing the round member into frictional engagement with the supporting member, said nipple being threaded in said supporting member and rotatable to effect longitudinal adjustment thereof so as to vary the compression of the spring means, a set screw extending within the supporting member to bear against the nipple to lock said nipple in place after adjustment, and a conduit adapted to carry a wire, said conduit communicating with the hole in the

round member and being secured to and projecting outwardly from the curved side of the round member.

7. A swivel jointed wired electrical fixture 5 adapted for universal angular adjustment comprising a round hollow member having a slot of greater length than width in its curved wall and extending peripherally thereof and a hole in its curved wall spaced peripherally from the ends of the slot, a supporting member, a nipple adapted 10 to carry a wire and supported at one end in said supporting member and extending through the slot in the round member and having a transversely extending shoulder adjacent its other end, 15 spring means compressed between the shoulder and the inner surface of the round member adjacent the slot for pressing the round member into frictional engagement with the supporting member, a concavo-convex strip of material adapted to cover the slot and engaging the inner 20 surface of the round member, a slot in the strip registering with but shorter than the slot in the round member, said strip being slidable within the round member when it is rotated relative to the nipple, and a conduit adapted to carry a wire, 25 said conduit communicating with the hole in the round member and being secured to and projecting outwardly from the curved side of the round member.

8. A swivel jointed wired electrical fixture 30 adapted for universal angular adjustment comprising a round hollow member having a slot of greater length than width in its curved wall and extending peripherally thereof and a hole in its curved wall spaced peripherally from the ends of the slot, a supporting member, a nipple adapted 35 to carry a wire and supported at one end in said supporting member and extending through the slot in the round member and having a transversely extending shoulder adjacent its other end, 40 spring means compressed between the shoulder and the inner surface of the round member adjacent the slot for pressing the round member into frictional engagement with the supporting member, a concavo-convex strip of material 45 adapted to cover the slot and engaging the inner surface of the round member, a slot in the strip registering with but shorter than the slot in the round member, said strip being slidable within 50 the round member when it is rotated relative to the nipple, a washer disposed on the nipple between the strip and the spring means, said washer being of sufficient width to cover the slot in the strip and being slidable relative to the strip, and a conduit adapted to carry a wire, 55 said conduit communicating with the hole in the round member and being secured to and projecting outwardly from the curved side of the round member.
